UNITED STATES PATENT OFFICE.

ALEXANDER F. MILNE, OF PITTSBURG, PENNSYLVANIA.

DESIGN FOR A BEDSTEAD.

SPECIFICATION forming part of Design No. 12,744, dated February 7, 1882.

Application filed December 24, 1881. Term of patent 7 years. *

To all whom it may concern:

Be it known that I, ALEXANDER F. MILNE, a subject of the Queen of England, residing at Pittsburgh, county of Allegheny, and State of Pennsylvania, have invented and produced a new and original Design for Bedsteads, of which the following is a specification, reference being had to the accompanying drawings, forming part thereof.

10 Figure 1 is a view of the head-board of my newly-designed bedstead. Fig. 2 represents the foot-board.

Heretofore iron bedsteads have been made with cast-iron uprights or posts held together by wrought-iron rods, without much regard to taste or attractive appearance, usefulness alone having been considered. To make them more in conformity with the taste of the present time, I have invented a new design, of which 20 the following is a full description.

The posts *a* of the bedstead and the ornamental parts connecting them at the head of the bedstead, and also the rail *b*, are to be cast in one piece. The central portion of this part 25 (called the "head-board") is in the form of a ring obliquely crossed by two bars, *c*, and furthermore divided by radial bars. The bars *c* extend beyond the circle *g* downward to the rail *b* and upward to horizontal bars *d*, by which 30 they are connected with the posts *a*. The length of the bars *d* coincides with one-half the vertical distance between the rail *b* and the bars *d*. Over the central piece, *g*, spanning the distance between the upper ends of

the bars *c*, at their junction with the rods *d*, is 35 an arch, *e*, that assists in supporting the whole. On a horizontal line with the center of the piece *g* meet the segments of circles *f*, centered at the posts *a*, occupying the space between the ends of the bars *c* and the posts. Beginning at the rail *b*, the posts are enlarged to the point where the segments *f* meet, and from this point upward they are again reduced to their thickness below the rail. The posts of the foot of the bedstead are like those of the 45 head, differing only in height. They are connected by the rail *b* and by bars *h*, that intersect each other diagonally at the center between the posts. The bars *h* at their intersection are surrounded by an ellipse, of which 50 the transverse axis extends to one-half the distance between the intersection of the bars and the posts. All the parts between the posts, excepting the rails, are light and of a uniform width, to which suitable ornaments may be 55 applied. My object is to furnish the design for a light but durable bedstead, easy to keep clean and pleasing to the eye.

Having thus described my design, I claim—

In a design for a bed, the combination of 60 the parts *a b c d e f g*, as shown and described.

In testimony whereof I affix my signature in presence of two witnesses.

ALEXANDER F. MILNE.
